BEAM HOLDING MEANS

Charles W. Eurey, Lincolnton, N.C., assignor to Excel, Inc., Lincolnton, N.C., a corporation of North Carolina
Filed Oct. 24, 1965, Ser. No. 504,510
9 Claims. (Cl. 211—44)

My invention relates to a rack for holding a beam during transport and storage and, more particularly, to such a rack having clamping means for preventing relative movement of a yarn carrying beam with respect to the rack in which the beam is supported.

In certain textile industries, fabric is produced from a large number of ends of yarn which are obtained by a fabric manufacturer in packages formed by winding the yarn onto a beam designed to be positioned on a textile fabric producing machine to supply the yarn for manufacturing the fabric. A beam, which is a generally cylindrical spool-like structure having a central axially extending barrel and two spaced apart end flanges connected to the barrel and known as beam heads, is shipped to a fabric manufacturer by a fiber manufacturer, stored by a fabric manufacturer until the yarn packaged on the beam is needed in the manufacturing process, and subsequently returned to the fiber manufacturer. In order to facilitate handling of beams during transport and storage, beam racks have heretofore been provided to receive and support beams.

In attempts to prevent relative movement of a beam with respect to such a rack, and the damage to the beam or the yarn wound thereon which is attendant to such movement, the horizontal members of a rack on which the beam heads rest have been provided with concave depressions formed to have approximately the contour of the outer circumference of the beam heads. Further, various blocking or chocking means have been provided to engage the outer periphery of the beam heads, to cooperate with the depressions in preventing lateral rolling movement of a beam. Although beam holding means of these types are widely used, damage to beams or yarn packaged thereon is not consistently avoided. More particularly, a beam may be jarred during transport, with resulting vertical bouncing on the rack or axial movement of the beam with respect to the rack damaging the beam or yarn carried thereon.

It is an object of this invention to provide a means for protecting a beam and the yarn wound thereon against damage during transport and storage, by locking the beam against relative displacement with respect to a rack in which it is carried. This is accomplished by providing means to lock the beam against vertical, lateral and axial movement with respect to a rack in which it is supported. In accordance with this invention, axial and vertical clamping forces are applied to a beam to restrain the beam against movement with respect to the rack.

Some of the objects and advantages of the invention having been stated, others will appear as the description proceeds when taken in connection with the accompanying drawing, in which:

FIGURE 1 is a perspective view of a rack incorporating clamping means in accordance with this invention;

FIGURE 2 is an elevation view of a portion of the rack of FIGURE 1, showing the clamping means in greater detail;

FIGURE 3 is a sectional view through a portion of the clamping means shown in FIGURE 2, taken along the line 3—3;

FIGURE 4 is a view similar to FIGURE 3, illustrating the position of the members of the clamping means in a beam unlocked position; and

FIGURE 5 is an elevation view taken as indicated by

2

the arrow 5 in FIGURE 3, and showing the cooperation of the clamping means with a beam.

Referring now more particularly to the drawing, a rack 10 is there shown which is adapted to receive and support a beam 11 (shown in phantom lines) during transport and storage of the beam. The beam 11 comprises a central axial cylinder 12, or barrel, of relatively small diameter and a pair of spaced end flanges or beam heads 14, assembled with the barrel 12 to form the generally cylindrical beam. Each beam head 14 has formed therein a central axially directed opening 15, into which suitable support members of a textile machine may enter to support the beam 11 during the textile fabric manufacturing process.

The rack 10 includes a pair of horizontally extending support members 16 which are adapted to receive and support the beam heads 14 of the beam 11. The upper surfaces of the support members 16 are provided with concave depressions 18 formed therein, which are arcuate and formed on a radius identical to the radius of the beam heads 14, to engage an arcuate portion of the circumferential periphery of the beam heads 14. Vertical standards 19, which provide protection for the beam 11 and yarn which may be wound thereon and which may provide for stacking of a number of racks and the beams carried thereby, side members 17 and beam end members 20 bracing the standards 19 complete the frame 10 structure.

In order to prevent relative movement of the beam with respect to the rack in which it is supported, this invention provides means to lock the beam 11 in position for transport or storage on the rack 10. In accordance with this invention, a clamping, or first, member 21 is mounted on each beam end member 20 of the rack 10, for axial and vertical movement with respect to a beam 11 supported on the rack and clamping engagement with the beam heads 14 of the beam. More particularly, each clamping member 21 has a horizontal portion 22 which rests upon the upper horizontal surface of a beam end member 20. A vertical portion extends upwardly from the horizontal portion 22, and has a clamping face 24 directed inwardly toward the end surface of a beam head 14, when a beam 11 is positioned on the rack 10. Outwardly of the beam end member 20, the clamping member 21 has a downwardly extending portion 25.

Each clamping member 21 is permitted to move yet retained in the desired position on the associated beam end member 20 by suitable means, such as a pair of clip members 26, secured to the beam end member 20. The clip members 26 provide a sufficiently large vertical clearance, between the lower surface of the clip members and the upper surface of the beam end member 20, to permit a small amount of vertical movement of the clamping member 21, such as approximately three-eighths of an inch. The clip members 26 extend over the horizontal portion 22 of the respective clamping member 21 a sufficient distance to engage the vertical portion thereof and limit the axial movement of the clamping member 21 to retain that member on the frame 10.

Each clamping member 21 additionally has a lateral projection 28 (FIGURES 3, 4 and 5) preferably in the form of a metal strip welded to the clamping face 24, which has a contour adapted to mate with at least the lower portion of the central opening 15 in a beam head 14, for reasons to be made more clear hereinafter. When the central opening 15 in a beam head 14 is circular (as here illustrated, for example, in FIGURE 5), the lateral projection 28 is given a part circular contour (FIGURE 5).

A second, or wedging, member 29 is provided for cooperation and engagement with each clamping member

21, and mounted on the frame 10 for movement between a beam unlocked position and a beam locked position in which the respective clamping member 21 is engaged and moved into clamping engagement with a beam supported on the rack. Preferably, each wedging member 29 is an elongate bar member pivotally connected, at one end thereof, to a beam end member 20, for pivotal movement between a beam locked position in which the member lies closely along the upper surface of the beam end member 20 (right end in FIGURE 1) and a beam unlocked position in which the wedging member 29 is raised (left end in FIGURE 1).

In order to move a clamping member 21 axially of the beam 11 supported on the rack 10 to engage the end surface of a beam head 14 with the clamping surface 24 of the clamping member, insert the lateral projection 28 into the central opening 15 of the beam head, and lock the beam against relative movement with respect to the rack 10, a cam surface is provided on one of each pair of cooperating members, to be engaged by the other of the pair of members upon movement of the wedging member into the beam locked position. Preferably, each clamping member 21 has a tapered cam surface 30, adapted to be engaged by the associated wedging member 29 on downward pivotal movement of the same, to move the clamping member 21 inwardly toward a beam 11, or axially of the beam.

Simultaneously with movement of a clamping member 21 axially of a beam 11 and into engagement with a beam head, the slippiness of the fit between the hook members 26 and the horizontal portion 22 of the clamping member 21, together with a slight vertical misalignment of the lateral projection 28 with respect to the central axial opening 15 of the beam head 14, permits the clamping member 21 to rise vertically a small amount, and no longer be directly supported by the upper horizontal surface of the beam end member 20 of the frame 10 (FIGURE 3). Accordingly, upon movement of the associated wedging member 29 downwardly to the beam locked position, the lower edge of the wedging member 29 engages a clamping block element 31 carried by the horizontal portion 22 of the clamping member 21. With this engagement, a downward force applied to the wedging member 29 is transmitted to the clamping member 21 and, by the engagement of the lateral projection 28 with the central opening 15 in a beam head 14, a vertically downward force is applied to the beam head 14 to lock the same downwardly in the concave depression 18.

Thus, two clamping forces are applied to a beam 11 upon actuation of the beam clamping means of this invention. A first force is directed axially of the beam 11, restrains the beam against axial movement relative to the rack, and results from the inward axial movement of the clamping members 21 and the engagement of the clamping faces 24 with the end faces of the beam heads 14. A second clamping force is a vertical downward force, restraining the beam against vertical movement relative to the rack and resulting from the engagement of the wedging members 29 with the clamping block elements 31, and transmitted through the lateral projections 28 to the central openings 15 in the beam heads 14. Further, due to the mating form of the projections 28 and the depressions 18, lateral movement of the beam 11 relative to the rack is restrained.

In order to assure that a beam 11 is maintained in the locked position, and that relative movement of the beam 11 with respect to the rack 10 is precluded, means are provided for securing the wedging members 29 in the beam locked position wherein the above described clamping forces are applied to the beam heads 14 of the beam 11. More particularly, the free end of each wedging member 29 preferably carries a first threaded member 32, in the form of a threaded rod having a handle at the upper end thereof and passing through a suitable bore in the

member 29. Each threaded rod 32 is adapted to be engaged with a second threaded member 34, such as a nut, mounted on the beam end member 20. Upon pivotal movement of each wedging member 29 downwardly, and into the beam locked position to result in the application of clamping forces to the beam 11, the associated threaded members 32, 34 may be engaged to draw the wedging member 29 downwardly and secure the same in the beam locked position.

10 In order to release a beam from a beam holding means constructed in accordance with this invention, the threaded members 32, 34 are disengaged and each wedging member 29 is moved to the beam unlocked position. Thereafter, the clamping members 21 are withdrawn from the beam heads 14, as by an operator grasping the downwardly extending portions 25, and the beam is released for removal from the rack.

15 It is considered apparent that the beam holding means and beam locking means herein described and illustrated 20 provide definite advantages over the heretofore used beam racks, particularly in providing for locking a beam against axial, vertical, or lateral movement relative to a beam rack. While it is preferred to provide a beam clamping means at each end of a beam rack, in order to positively 25 secure both ends of a beam in locked position, it is to be understood that a clamping member located at one end of a frame and having a lateral projection and cooperating with a wedging member as described above would give 30 rise to axial and vertical forces adequate to secure a beam in locked position, were the opposite beam head butted against the adjacent beam end member.

35 In the drawings and specification there has been set forth a preferred embodiment of the invention and, although specific terms are employed, they are used in a generic and descriptive sense only and not for purposes of limitation, the scope of the invention being defined in the claims.

I claim:

1. In combination with a rack for receiving and supporting during transport and storage a generally cylindrical beam having a pair of spaced apart heads and a central axially directed opening in each head, means for securing a beam against displacement relative to the rack so that damage to the beam is avoided, said means comprising:
  - a first member mounted on the rack for axial movement relative to the beam supported on the rack and adapted to engage a beam head thereof and the central opening therein,
  - a second member for engaging said first member and being movable between beam locked and unlocked positions,
  - one of said members having a cam surface thereon adapted to be engaged by the other of said members upon movement of said second member to the beam locked position so that said first member is moved axially of the beam into engagement with the beam head thereof and the central opening therein, and means for securing said second member in the beam locked position.
2. The combination as claimed in claim 1 wherein said first member has a lateral projection contoured to enter into and mate with a lower portion of the central opening upon axial movement of said first member toward the beam.
3. The combination as claimed in claim 1 wherein said cam surface is on said first member.
4. The combination as claimed in claim 1 wherein said second member is movable downwardly into beam locking position to exert a downward loading force on said first member.
5. The combination as claimed in claim 4 wherein said second member is an elongate bar member pivotally connected at one end thereof to the rack.

6. The combination as claimed in claim 1 wherein said last mentioned means comprises cooperating threaded members on said second member and the rack.

7. Apparatus for receiving and supporting during transport and storage a generally cylindrical beam having a pair of spaced apart heads and a central axially directed opening in each head, the apparatus comprising:

a rack having horizontally extending members for receiving and supporting the heads of a beam,
a clamping member mounted on the rack for axial movement relative to the beam supported on said rack and adapted to engage a beam head thereof, said clamping member having a lateral projection contoured to enter into and engage a lower portion of the central opening therein,
a wedging member for engaging said clamping member and being movable between beam locked and unlocked positions,
one of said clamping or wedging members having a cam surface thereon adapted to be engaged by the other of said members upon movement of said wedging member to the beam locked position so that said clamping member is moved axially of the beam into

engagement with the beam head thereof and into the central opening therein, and means for securing said wedging member in the beam locked position.

5 8. An apparatus as claimed in claim 7 wherein said cam surface is on said first member and said second member is movable downwardly into beam locking position to exert a downward loading force on said first member.

10 9. An apparatus as claimed in claim 8 wherein said means comprises cooperating threaded members on said second member and the rack.
